ROTATABLE BAFFLE FOR KITCHEN RANGE VENTILATORS

Edward Graswich, Walnut Creek, and Jack W. Cedurquist, San Francisco, Calif., assignors, by mesne assignments, to Dohrmann Sales Company, San Francisco, Calif., a corporation of California

Filed May 25, 1961, Ser. No. 125,889
4 Claims. (Cl. 55—404)

This invention relates to ventilator apparatus for exhausting cooking gases from cooking surfaces in general. More particularly this invention relates to ventilator apparatus employing a rotatable baffle.

An object of this invention is to provide an improved ventilator structure for use with cooking ranges and the like in which there is provided a rotatable baffle adapted to rotate at speeds of the order of 500 r.p.m.

Another object of this invention is to provide an improved ventilator structure for use with cooking ranges with a rotatable baffle structure constructed so as to be able to withstand temperatures of the order of 450 degrees F. under certain operating conditions.

A further object of this invention is to provide an improved ventilator structure for use with cooking ranges with a rotatable baffle structure that is removable so that it may be removed and cleaned in commercial dish-washing equipment with steam and detergents.

Another object of this invention is to provide an improved ventilator structure for use with cooking ranges with a rotatable baffle structure which is provided with a bearing structure that is adapted to withstand relatively high temperatures under certain operating conditions and which is adapted to rotate at relatively high speeds.

Another object of this invention is to provide an improved ventilator structure for exhausting cooking gas from cooking surfaces in which there is provided a rotatable baffle structure that may be used in any desired position including vertical, horizontal and other positions.

Other and further objects of this invention will be apparent to those skilled in the art to which it relates from the following specification, claims and drawing.

In accordance with this invention, there is provided an improved ventilator structure with a rotatable baffle for use with cooking ranges to exhaust the cooking gases therefrom. This rotatable baffle structure has several advantages over similar structures in that it is constructed to rotate at relatively high speeds and is adapted to withstand relatively high temperatures under certain operating conditions.

Referring to the drawing briefly:

FIG. 1 is a sectional view showing a ventilator structure provided with a rotatable baffle of this invention;

FIG. 2 is a detail view of the rotatable baffle; and

FIG. 3 is a sectional view taken along the line 3—3 of FIG. 2.

Referring to the drawing in detail, there is illustrated an embodiment of this invention employing a sheet metal structure 10 defining a passage for exhausting cooking gases from a cooking surface located below the structure. This sheet metal structure is provided with a stack 11 extending upward, only a part of which is shown and inside of which there may be provided a motor driven exhaust fan (not shown). The sheet metal structure is also provided with a back wall 12, a front wall 13 and an inner inclined wall 14 which is provided with a lip forming the bottom wall of an opening which is adapted to be closed by the fire door 15 and through which opening the cooking gases pass toward the opening 21 of the rotatable baffle enclosure 17. This enclosure is of generally square

2

configuration as shown in FIG. 3 and it is provided with a top wall 18 having a large opening 22 therein and a bottom wall 19 in which the opening 21 is provided. Both the top wall 18 and the bottom wall 19 may be frictionally held in this enclosure or suitable conventional fastening means may be provided thereto so that either one or both of these walls may be removed from the enclosure and the rotatable baffle may be removed through the open top. The member 14 of the ventilator wall structure may be made removable so as to provide access to the rotatable baffle enclosure for removal thereof for cleaning and servicing if necessary.

The rotatable baffle is provided with a frame 40 of generally rectangular configuration and this frame includes a top member 40a, side members 40b and 40c, and bottom member 40d. The side members 40b and 40c may be integral with the bottom member 40d and may be shaped simply by bending the end portions of the bottom member 40d into vertical positions. Thereafter the end portions of the top member 40a are attached by welding or the like to the tops of the side members 40b and 40c respectively. The ends of the member 40a extend beyond the tops of the side members to engage the in-turned edge portion of the enclosure 17 as shown in FIG. 2 to support the baffle structure in the enclosure.

A round shaft 23 is provided to the rotatable baffle and the ends of this shaft are attached to the top member 40a and to the bottom member 40d by means of machine screws 22a and 21a, respectively, so that this shaft is fixedly held in the frame. The baffle structure is provided with a circular plate member 24 and a plurality of vanes 25, each of arcuate shape, are attached to the bottom surface of this plate member by means of rivets 25a as shown in FIG. 3. This circular plate member 24 is provided with a central hole for receiving a shoulder of the lower hub 27. The upper hub member 26 is positioned over this hole and the two hub members are riveted against the plate member by means of the rivets 28 which hold the hub members and plate 24 in assembled relation. Bearing members 29 and 30 which are of carbon, graphite or similar material adapted to withstand relatively high temperatures are press-fitted into the central holes provided in hub members 26 and 27 respectively. These bearing members are provided with shoulders which abut the outer surfaces

45 of the respective hub members and extend outward beyond these hub members as shown. Collars 31 and 32 are fixed to the shaft 23 by means of set screws 33 and 34 respectively, and these collars are positioned above and below the bearing members 29 and 30 respectively. The faces of these collars facing the bearing members are provided with polished surfaces so as to function as thrust bearing surfaces for the end surfaces of the bearing members 29 and 30 whereby this rotatable baffle structure may be used in its horizontal, vertical or in different angular positions, depending on the installation in which it is employed.

The vanes 25 are of arcuate construction and they are attached to the plate 24 so that adjacent ones of the vanes define curved channels therebetween which expand toward the circumference. The cooking gases passing through these channels engage these blades or vanes and impart rotation to the plate member 24 to which they are attached. A sufficient number of these vanes 25 is provided to the plate member 24 to impart relatively high speed rotation on the order of 500 r.p.m. to the rotatable baffle structure, thereby providing a baffle structure having improved efficiency for removing grease from the grease laden cooking gases being exhausted therethrough. Also by providing a plurality of these vanes spaced relatively close, the resulting rotatable baffle structure provides a relatively large surface of contact for the cooking gases

on which the greases to be deposited and collected from the cooking gases may be collected.

This rotatable baffle structure may be subject to cleaning in commercial dishwashing equipment which make use of steam and detergents. The side members 40b and 40c of the rotatable baffle structure are slidably positioned in the slides 17b and 17d, respectively, which are attached to the members 17a and 17c. These latter members are attached to the inner side walls of the enclosure 17. Thus the rotatable baffle structure may be removed from the slides 17b and 17d by lifting it up out of these slides.

While we have shown a preferred embodiment of the invention it will be understood that the invention is capable of variation and modification from the form shown so that its scope should be limited only by the scope of the claims appended hereto.

What we claim is:

1. In a ventilating structure for extracting grease from the grease-laden gases of a cooking surface, said ventilating structure being adapted for use at relatively high temperatures, the combination comprising wall structure forming a passage for exhausting cooking gases extracted from above said cooking surface, rotatable grease collecting baffle structure, means for supporting said rotatable baffle structure in said passage, said rotatable baffle structure comprising a substantially flat circular member having a hole substantially in the center thereof, hub means positioned in said hole, said hub means having opposing members, means for fixedly attaching said opposing members of said hub means to opposite sides of said substantially flat member so that said substantially flat member is clamped between said opposing members, opposing heat resistant bearing means press-fitted into said opposing members of said hub means, said bearing means extending out of said hub means to form thrust bearing surfaces on the ends thereof, a shaft positioned in said bearing means for rotatably supporting said bearing means, means fixedly attached to said shaft on each side of said bearing means having thrust bearing surfaces for cooperating with the thrust bearing ends of said bearing means so that said baffle structure may be positioned for use in any one of a plurality of positions including a horizontal or vertical position, said baffle structure having a plurality of blades attached to one side of said substantially flat member and extending from the circumference thereof inward and means for guiding flow of the cooking gases through said blades to impart rotation to said baffle structure.

2. In a ventilating structure for extracting grease from the grease-laden gases of a cooking surface, said ventilating structure being adapted for use at relatively high temperatures, the combination comprising wall structure forming a passage for exhausting cooking gases extracted from above said cooking surface, rotatable grease collecting baffle structure, said wall structure having an enclosure for said rotatable baffle structure, means for supporting said rotatable baffle structure in said enclosure, said enclosure having inlet and outlet openings therein on opposite sides of said baffle structure, said rotatable baffle structure comprising a substantially flat circular member having a hole substantially in the center thereof, hub means positioned in said hole, said hub means having opposing members, means for fixedly attaching said opposing members of said hub means to opposite sides of said substantially flat member so that said substantially flat member is clamped between said opposing members, opposing heat resistant bearing means press-fitted into said opposing members of said hub means, said bearing means extending out of said hub means to form thrust bearing surfaces on the ends thereof, a shaft positioned in said bearing means for rotatably supporting said bearing means, means fixedly attached to said shaft on each side of said bearing means having thrust bearing surfaces for cooperating with the thrust bearing ends of said bearing means so that said baffle structure may be positioned for use in any one of a plurality of positions

including a horizontal or vertical position, said supporting means comprises a frame, means for attaching said shaft to said frame, said frame having members for slidably engaging said enclosure whereby said baffle structure is adapted to be removed from said enclosure for cleaning, said baffle structure having a plurality of blades attached to one side of said substantially flat member and extending substantially from the circumference thereof inward, said blades extending partly over said inlet opening whereby the cooking gases are guided to said blades so to impart rotation to said baffle structure.

3. In a ventilating structure for extracting grease from the grease-laden gases of a cooking surface, said ventilating structure being adapted for use at relatively high temperatures, wall structure forming a passage for exhausting cooking gases extracted from above said cooking surface, rotatable grease collecting baffle structure, said wall structure having an enclosure for said rotatable baffle structure, means for supporting said rotatable baffle structure in said enclosure, said rotatable baffle structure comprising a substantially flat circular member having a hole substantially in the center thereof, hub means positioned in said hole, said hub means having opposing members, means for fixedly attaching said opposing members of said hub means to opposite sides of said substantially flat member so that said substantially flat member is clamped between said opposing members, opposing heat resistant bearing means press-fitted into said opposing members of said hub means, said bearing means extending out of said hub means to form thrust bearing surfaces on the ends thereof, a shaft positioned in said bearing means for rotatably supporting said bearing means, means fixedly attached to said shaft on each side of said bearing means having thrust bearing surfaces for cooperating with the thrust bearing ends of said bearing means so that said baffle structure may be positioned for use in any one of a plurality of positions including a horizontal or vertical position, said supporting means comprises a frame, means for attaching said shaft to said frame, said frame having side members, slides for slidably receiving said side members, means for attaching said slides to said enclosure whereby said baffle structure is adapted to be removed from said enclosure for cleaning, said baffle structure having a plurality of blades attached to one side of said substantially flat member and extending substantially from the circumference thereof inward, said wall structure having means for guiding flow of the cooking gases through said blades to cause rotation of said baffle structure.

4. In a ventilating structure for extracting grease from the grease-laden gases of a cooking surface, said ventilating structure being adapted for use at relatively high temperatures, the combination comprising wall structure forming a passage for exhausting cooking gases extracted from above said cooking surface, rotatable grease collecting baffle structure, means for supporting said rotatable baffle structure in said passage, said rotatable baffle structure comprising a substantially flat circular member having a hole substantially in the center thereof, hub means positioned in said hole, said hub means having opposing members, means for fixedly attaching said opposing members of said hub means to opposite sides of said substantially flat member so that said substantially flat member is clamped between said opposing members, opposing heat resistant bearing means press-fitted into said opposing members of said hub means, said bearing means extending out of said hub means to form thrust bearing surfaces on the ends thereof, a shaft positioned in said bearing means for rotatably supporting said bearing means, means fixedly attached to said shaft on each side of said bearing means having thrust bearing surfaces for cooperating with the thrust bearing ends of said bearing means so that said baffle structure may be positioned for use in any one of a plurality of positions including a horizontal or vertical position, said supporting

means comprises a frame, means for attaching said shaft to said frame, said frame having members for slidably engaging said wall structure whereby said baffle structure is adapted to be removed from said wall structure for cleaning, said baffle structure having a plurality of blades attached to one side of said substantially flat member and extending substantially from the circumference thereof inward, adjacent ones of said blades defining curved and expanding channels therebetween extending from said hub means substantially to the circumference 10 of said substantially flat member, said wall structure hav-

ing means for guiding the cooking gases to said channels between said blades so that rotation is imparted to said baffle structure.
